(57) **CLAIM**

The ornamental design for an adapter for electric charger, as shown and described.

DESCRIPTION

FIG. 1 is a front perspective view of adapter for a electric charger, according to the claimed design.

FIG. 2 is a front view thereof.

FIG. 3 is a rear view thereof.

FIG. 4 is a left side view thereof.

FIG. 5 is a right side view thereof.

FIG. 6 is a top plan view thereof.

FIG. 7 is a bottom view thereof; and,

FIG. 8 is a bottom perspective view.

1 Claim, 5 Drawing Sheets
